UNITED STATES PATENT OFFICE.

MILTON C. J. BILLINGHAM, OF KALAMAZOO, MICHIGAN, ASSIGNOR OF ONE-HALF TO HENRY VANDER HORST, OF KALAMAZOO, MICHIGAN.

PAPER-STOCK-TREATING MACHINE.

1,276,864.

Specification of Letters Patent. Patented Aug. 27, 1918.

Application filed June 10, 1918. Serial No. 239,279.

To all whom it may concern:

Be it known that I, MILTON C. J. BILLINGHAM, a citizen of the United States, residing at the city and county of Kalamazoo, State 5 of Michigan, have invented certain new and useful Improvements in Paper-Stock-Treating Machines, of which the following is a specification.

This invention relates to improvements in 10 paper stock treating machines.

The main objects of this invention are:

First, to provide an improved stock treating machine for washing and disintegrating paper stock which is of very large capacity.

Second, to provide an improved machine 15 for washing and disintegrating paper stock which greatly reduces the time commonly required for washing paper stock.

Third, to provide an improved machine 20 of the class described which is adapted for use in de-inking and disintegrating printed paper for use as paper stock.

Fourth, to provide an improved machine 25 of the class described which produces a superior product.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing, forming a part of this specification, in which:

Figure I is a rear end elevation of a structure embodying the features of my invention.

Fig. II is a front end elevation.

Fig. III is a detail plan view of the rear end of the structure.

Fig. IV is a detail longitudinal section 40 on a line corresponding to line 4—4 of Figs. I, II, III and V, the parts being shown in full lines.

Fig. V is a transverse section on a line corresponding to line 5—5 of Fig. IV.

Fig. VI is an enlarged transverse detail 50 section showing details of the cylinder structure.

Fig. VII is a detail view partially in transverse section of the agitator shaft.

Fig. VIII is a detail transverse section 55 on a line corresponding to line 8—8 of Fig. IV.

Fig. IX is a detail longitudinal section of a modified embodiment of my invention.

Fig. X is a transverse section of another modified form or embodiment of my invention.

Fig. XI is a detail section on a line corresponding to line 11—11 of Fig. X.

Fig. XII is a plan view of another modification provided with means for re-passing 60 the stock through the machine.

In the drawing similar reference characters refer to similar parts throughout the several views, and the sectional views are taken looking in the direction of the little 70 arrows at the ends of the section lines.

Referring to the drawing, I provide a trough 1 of such size as to receive the cylinder 2 which is rotatably mounted therein. The ends of the trough are provided with 75 bearings 3 for the tubular gudgeons 4 of the cylinder.

The body walls 5 of the cylinder are 80 foraminated. Within the cylinder is a spiral 6 having a rearward lead, the spiral being, for convenience in manufacture, built up of segments 7. Between these segments are longitudinal bars 8. To these bars are secured forwardly curved blades 9, the blades being disposed between the turns of the spiral and coacting therewith to provide a spiral series of dippers which, as the cylinder revolves, carry the stock up to the point where it is discharged by gravity from the dippers.

Within the spiral I provide a series of compartments 10 having inlet openings 11 into which the stock is discharged from the blades. These compartments have discharge openings 12 on the downstroke side 95 of the cylinder. As the cylinder revolves it carries the stock up and discharges it into the compartments from which it overflows into the cylinder. These spirally arranged dippers discharge the stock to succeeding 100 compartments so that it is repeatedly passed through the compartments and discharged therefrom and advanced toward the rear of the cylinder.

At the rear of the cylinder I provide a discharge trough 13 positioned so that the rear dippers discharge thereto. This trough has an outlet 14 delivering to the conveyer pipe 15.

Disposed axially of the cylinder and 110 through the compartments and trough is a shaft 16 having propeller-like blades 17.

thereon arranged within the compartments so that the stock is violently agitated within the confined area of these compartments to break up lumps of stock or disintegrate the same. The stock being passed through repeated compartments is subjected to a series of disintegrating and washing operations. The length of the machine may, of course, be varied as circumstances render desirable.

10 On the shaft 16 is a discharge screw 18 which drives the stock from the trough into the discharge spout or pipe.

To prevent clogging of the cylinder and also to further disintegrate the stock I 15 provide a spray pipe 19 positioned so as to spray the stock as it is discharged from the dippers. To further break up and wash the stock I provide sprays 20 and 21 positioned so as to discharge against the stock or across 20 the path of the stock as it is discharged by the dippers into the compartments.

I also preferably provide a spray 22 positioned so that it discharges across the path of the stock as it is delivered from the compartments. These sprays not only assist in 25 washing the stock but also in disintegrating it.

To facilitate cleaning of the apparatus the shaft 16 is preferably in the form of a pipe 30 having spray openings 23. Water may be discharged through this pipe while operating on stock. The stock is delivered to the machine through the pipe 24.

In the modification shown in Fig. IX the 35 dippers 25 are not disposed spirally but the compartments 26 are disposed diagonally so that the stock in passing through the compartments is advanced one step as it discharges from the compartments into the succeeding annular series of dippers.

In the modification shown in Figs. X and XI the beaters or agitating blades are omitted, the structure being especially designed 45 as a washer, the disintegrating features of the blades being omitted. In this structure the dippers discharge across the inclined corrugated plate 27 having a series of spray pipes 28 discharging across the path of the stock. The means for driving the cylinder 50 and the shaft form no part of this invention. They are conventionally illustrated but I do not deem it necessary to describe the same herein.

In Fig. XIII I show means for repeatedly 55 passing the stock through the machine which is sometimes desirable, especially in de-inking processes. In this construction the discharge pipe 29 delivers the stock to a tank 30 from which it is returned to the 60 machine through the pump 31. The pump and a driving motor 32 are shown conventionally.

My improved paper stock treating machine is very efficient for washing and disintegrating paper stock and has also a very

large capacity, it being capable of handling much greater quantities of stock in a given time than the ordinary washer now commonly employed. The structure is also advantageous for use in de-inking processes 70 as it is effective in breaking up or disintegrating paper and like material into their separate fibers.

I have illustrated and described my improvements in certain embodiments which I 75 contemplate and which I believe will enable the adaptation of my improvements to the various uses for which they are desirable by those skilled in the art to which this invention relates.

Having thus described my invention, what I claim as new and desire to secure by Letters Patent, is:

1. In a structure of the class described, the combination of a tank, a foraminated cylinder mounted to revolve therein, an internal spiral for said cylinder having a rearward lead, a series of compartments disposed within said spiral, blades disposed between the turns of the spiral and coacting therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, a discharge trough at the rear of said compartments into which the dippers at the rear end of the cylinder discharge, a shaft disposed axially of the cylinder and through said compartments and discharge trough, blades on said shaft within said compartments, a discharge 100 screw on said shaft within said discharge trough, a spray directed through said cylinder at the point of discharge of its dippers, sprays directed across the path of the stock as it is delivered to and from said compartments, and means for feeding stock to the front end of said cylinder.

2. In a structure of the class described, the combination of a tank, a foraminated cylinder mounted to revolve therein, an internal spiral for said cylinder having a rearward lead, a series of compartments disposed within said spiral, blades disposed between the turns of the spiral and coacting therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, a shaft disposed axially of the cylinder and through said compartments, 115

blades on said shaft within said compartments, a spray, directed through said cylinder at the point of discharge of its dippers, sprays directed across the path of the stock 5 as it is delivered to and from said compartments, and means for feeding stock to the front end of said cylinder.

3. In a structure of the class described, the combination of a tank, a foraminated cylinder mounted to revolve therein, an internal spiral for said cylinder having a rearward lead, a series of compartments disposed within said spiral, blades disposed between the turns of the spiral and coating therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, a discharge trough at the rear of said compartments into which the dippers at the rear end of the cylinder discharge, a shaft disposed axially of the cylinder and through said compartments and discharge trough, blades on said shaft within said compartments, a discharge screw on said shaft within said discharge trough, sprays directed across the path of the stock as it is delivered to and from said compartments, and means for feeding stock to the front end of said cylinder.

4. In a structure of the class described, the combination of a tank, a foraminated cylinder mounted to revolve therein, an internal spiral for said cylinder having a rearward lead, a series of compartments disposed within said spiral, blades disposed between the turns of the spiral and coacting therewith to provide a series of spirally disposed dippers which discharge the stock 40 into said compartments as the cylinder revolves, the dippers of succeeding spirals being adapted to discharge to succeeding compartments, said compartments having discharge openings on the downstroke side of 45 the cylinder so that the stock is passed through the compartments and advanced in the cylinder, a shaft disposed axially of the cylinder and through said compartments, 50 blades on said shaft within said compartments, sprays directed across the path of the stock as it is delivered to and from said compartments, and means for feeding stock 55 to the front end of said cylinder.

5. In a structure of the class described, the combination of a tank, a foraminated cylinder mounted to revolve therein, an internal spiral for said cylinder having a rearward lead, a series of compartments disposed within said spiral, blades disposed between the turns of the spiral and coacting

therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, a discharge trough at the rear of said compartments into which the dippers at the rear end of the cylinder discharge, a shaft disposed axially of the cylinder and through said compartments and discharge trough, blades on said shaft within said compartments, a discharge screw on said shaft within said discharge trough, and means for feeding stock to the front end of said cylinder.

6. In a structure of the class described, 85
the combination of a tank, a foraminated
cylinder mounted to revolve therein, an in-
ternal spiral for said cylinder having a rear-
ward lead, a series of compartments dis-
posed within said spiral, blades disposed 90
between the turns of the spiral and coating
therewith to provide a series of spirally dis-
posed dippers which discharge the stock into
said compartments as the cylinder revolves,
the dippers of succeeding spirals being 95
adapted to discharge to succeeding compart-
ments, said compartments having discharge
openings on the downstroke of the cylinder
so that the stock is passed through the com-
partments and advanced in the cylinder, a 100
shaft disposed axially of the cylinder and
through said compartments, blades on said
shaft within said compartments, and means
for feeding stock to the front end of said
cylinder, 105

7. In a structure of the class described, the combination of a tank, a foraminated cylinder mounted to revolve therein, a series of internal spirally disposed dippers for said cylinder, a series of compartments disposed within said dippers so that the dippers of succeeding spirals discharge to succeeding compartments, said compartments having discharge openings on the down-stroke side of the cylinder so that the stock is passed through the compartments and advanced in the cylinder by the rotation of the cylinder, a discharge trough at the rear of said compartments into which the dippers at the rear end of the cylinder discharge, a shaft disposed axially of the cylinder and through said compartments and discharge trough, blades on said shaft within said compartments, a discharge screw on said shaft within said discharge trough, a spray directed through said cylinder at the point of discharge of its dippers, and sprays directed across the path of the stock as it is delivered to and from said compartments.

8. In a structure of the class described, 130

- the combination of a tank, a foraminated cylinder mounted to revolve therein, a series of internal spirally disposed dippers for said cylinder, a series of compartments disposed within said dippers so that the dippers of succeeding spirals discharge to succeeding compartments, said compartments having discharge openings on the downstroke side of the cylinder so that the stock is passed through the compartments and advanced in the cylinder by the rotation of the cylinder, a shaft disposed axially of the cylinder and through said compartments, blades on said shaft within said compartments, a spray directed through said cylinder at the point of discharge of its dippers, and sprays directed across the path of the stock as it is delivered to and from said compartments. 9. In a structure of the class described, the combination of a tank, a foraminated cylinder mounted to revolve therein, a series of internal spirally disposed dippers for said cylinder, a series of compartments disposed within said dippers so that the dippers of succeeding spirals discharge to succeeding compartments, said compartments having discharge openings on the downstroke side of the cylinder so that the stock is passed through the compartments and advanced in the cylinder by the rotation of the cylinder, a discharge trough at the rear of said compartments into which the dippers at the rear end of the cylinder discharge, a shaft disposed axially of the cylinder and through said compartments and discharge trough, blades on said shaft within said compartments, and a discharge screw on said shaft within said discharge trough. 10. In a structure of the class described, the combination of a tank, a foraminated cylinder mounted to revolve therein, a series of internal spirally disposed dippers for said cylinder, a series of compartments disposed within said dippers so that the dippers of succeeding spirals discharge to succeeding compartments, said compartments having discharge openings on the downstroke side of the cylinder so that the stock is passed through the compartments and advanced in the cylinder by the rotation of the cylinder, a shaft disposed axially of the cylinder and through said compartments, and blades on said shaft within said compartments. 11. In a structure of the class described, the combination of a foraminated cylinder, an internal spiral for said cylinder having a rearward lead, a series of compartments disposed within said spiral, blades disposed between the turns of the spiral and coacting therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, and sprays directed across the path of the stock. 12. In a structure of the class described, the combination of a foraminated cylinder, an internal spiral for said cylinder having a rearward lead, a series of compartments disposed within said spiral, blades disposed between the turns of the spiral and coacting therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder, and means for agitating the stock within the compartments. 13. In a structure of the class described, the combination of a foraminated cylinder, an internal spiral for said cylinder having a rearward lead, a series of compartments disposed within said spiral, and blades disposed between the turns of the spiral and coacting therewith to provide a series of spirally disposed dippers which discharge the stock into said compartments as the cylinder revolves, the dippers of succeeding spirals being adapted to discharge to succeeding compartments, said compartments having discharge openings on the downstroke side of the cylinder so that the stock is passed through the compartments and advanced in the cylinder. 14. In a structure of the class described, the combination of a foraminated cylinder, an internal spiral for said cylinder having a rearward lead, blades disposed between the turns of the spiral and coacting therewith to provide a series of spirally disposed dippers, a series of compartments into which said dippers discharge, the dippers of succeeding spirals being adapted to discharge to succeeding compartments, said compartments discharging on the downstroke side of the cylinder so that the stock is passed through the compartments and advanced in the cylinder, and sprays directed against the falling stock. 15. In a structure of the class described, the combination of a foraminated cylinder, a series of internal spirally disposed dippers for said cylinder, a series of compartments disposed within said dippers so that the dippers of succeeding spirals discharge to succeeding compartments, said compartments having discharge openings on the downstroke side of the cylinder so that the stock is passed through the compartments and advanced in the cylinder, and sprays directed across the path of the stock.

ed across the path of the stock discharged from the dippers.

16. In a structure of the class described, the combination of a foraminated cylinder, 5 a series of internal spirally disposed dippers for said cylinder, a series of compartments disposed within said dippers so that the dippers of succeeding spirals discharge to succeeding compartments, said compartments 10 having discharge openings on the down-stroke side of the cylinder so that the stock is passed through the compartments and advanced in the cylinder, and means for agitating the stock within said compartments.

15. 17. In a structure of the class described, the combination of a foraminated cylinder, a series of internal spirally disposed dippers for said cylinder, and a series of compartments disposed within said dippers so that 20 the dippers of succeeding spirals discharge to succeeding compartments, said compartments having discharge openings on the downstroke side of the cylinder so that the stock is passed through the compartments 25 and advanced in the cylinder.

18. In a structure of the class described, the combination of a foraminated cylinder, a series of internal dippers adapted to elevate and discharge the stock as the cylinder 30 rotates, a series of compartments into which the stock is discharged by said dippers, said dippers and compartments coacting to advance the stock, a discharge trough at the rear of the compartments into which the 35 dippers at the rear end of the cylinder discharge, a shaft disposed through said compartments and discharge trough, blades on said shaft within said compartments, a discharge screw on said shaft within said discharge 40 trough, and sprays directed across the path of the stock between its discharge from said dippers and return to the cylinders.

19. In a structure of the class described, 45 the combination of a foraminated cylinder, a series of internal dippers adapted to elevate and discharge the stock as the cylinder rotates, a series of compartments into which the stock is discharged by said dippers, said 50 dippers and compartments coacting to advance the stock, a shaft disposed through said compartments, blades on said shaft within said compartments, and sprays directed across the path of the stock between 55 its discharge from said dippers and return to the cylinder.

20. In a structure of the class described, the combination of a foraminated cylinder, a series of internal dippers adapted to elevate and discharge the stock as the cylinder 60 rotates, a series of compartments into which

the stock is discharged by said dippers, said dippers and compartments coacting to advance the stock, a discharge trough at the rear of the compartments into which the 65 dippers at the rear end of the cylinder discharge, a shaft disposed through said compartments and discharge trough, blades on said shaft within said compartments, and a discharge screw on said shaft within said 70 discharge trough.

21. In a structure of the class described, the combination of a foraminated cylinder, a series of internal dippers adapted to elevate and discharge the stock as the cylinder 75 rotates, a series of compartments into which the stock is discharged by said dippers, said dippers and compartments coacting to advance the stock, a shaft disposed through said compartments, and blades on said shaft 80 within said compartments.

22. In a structure of the class described, the combination of a foraminated cylinder, a series of internal dippers adapted to elevate and discharge the stock as the cylinder 85 rotates, a series of compartments into which the stock is discharged from said dippers, said dippers and compartments coacting to advance the stock through the cylinder, means for agitating the stock within the 90 compartments, and sprays directed across the path of the stock between its discharge from the dippers and return to the cylinder.

23. In a structure of the class described, the combination of a foraminated cylinder, 95 a series of internal dippers adapted to elevate and discharge the stock as the cylinder rotates, a series of compartments into which the stock is discharged from said dippers, said dippers and compartments coacting to 100 advance the stock through the cylinder, and sprays directed across the path of the stock between its discharge from the dippers and return to the cylinder.

24. In a structure of the class described, 105 the combination of a foraminated cylinder, a series of internal dippers adapted to elevate and discharge the stock as the cylinder rotates, a series of compartments into which the stock is discharged from said dippers, 110 said dippers and compartments coacting to advance the stock through the cylinder, and means for agitating the stock within the compartments.

In witness whereof, I have hereunto set 115 my hand and seal in the presence of two witnesses.

MILTON C. J. BILLINGHAM. [L. S.]
